CLAIM

The ornamental design for a ballast box for the bed of a pickup truck, as shown and described.

DESCRIPTION

FIG. 1 is an exploded perspective view of a truck weight box showing my new design;

FIG. 2 is an enlarged side elevation view thereof with the cover omitted for convenience of illustration, the opposite side being a mirror image of that shown;

FIG. 3 is an end elevation view of FIG. 2, the opposite end being a mirror image of that shown;

FIG. 4 is an enlarged top plan view of FIG. 2;

FIG. 5 is an enlarged side elevation view of the cover thereof shown separately for convenience of illustration;

FIG. 6 is an end elevation view of FIG. 5; and,

FIG. 7 is a bottom plan view of FIG. 5.

The bottom of the box and top of the cover therefor are understood to be flat and unornamented.

FIG. 2.

FIG. 3.

FIG. 4.

FIG. 7.

FIG. 5.

FIG. 6.
